(57) **CLAIM**

The ornamental design for a hair dryer, as shown and described.

DESCRIPTION

FIG. 1 is a perspective view of a hair dryer showing the inventive design.

FIG. 2 is a second perspective view of said hair dryer showing the inventive design.

FIG. 3 is a front view of said hair dryer showing the inventive design.

FIG. 4 is a rear view of said hair dryer showing the inventive design.

FIG. 5 is a left side view of said hair dryer showing the inventive design.

FIG. 6 is a right side view of said hair dryer showing the inventive design.

FIG. 7 is a top view of said hair dryer showing the inventive design.

FIG. 8 is a bottom view of said hair dryer showing the inventive design; and,

FIG. 9 is an enlarged view of the area labeled “9” in FIG. 6 of said hair dryer showing the inventive design.

The evenly dashed broken lines in the drawings depict portions of the hair dryer that form no part of the claimed design.

The long dash/short dash lines in the drawings depict the boundaries of the enlarged view and form no part of the claimed design.

1 Claim, 9 Drawing Sheets
